UNITED STATES PATENT OFFICE.

JOSEPH M. BLAKE, OF BUFFALO, NEW YORK.

LUMBER-WAGON.

SPECIFICATION forming part of Letters Patent No. 495,194, dated April 11, 1893.

Application filed November 14, 1892. Serial No. 451,862. (No model.)

To all whom it may concern:

Be it known that I, JOSEPH M. BLAKE, a citizen of the United States, residing at Buffalo, in the county of Erie and State of New

5 York, have invented certain new and useful Improvements in Lumber-Wagons; and I do hereby declare the following to be a full, clear, and exact description of the invention, such as will enable others skilled in the art to 10 to which it appertains to make and use the same, reference being had to the accompanying drawings, and to figures of reference marked thereon, which form a part of this specification.

15 My invention relates to that class of lumber wagons which are so constructed and arranged that their loads can be dumped entire instead of being removed piece by piece and it consists of certain improvements in a 20 form of lumber wagon for which Letters Patent No. 365,569 were granted to me on June 28, 1887. In such wagon friction rollers were provided resting upon the top face of and extending transversely across the sills and adapted to reciprocate thereon for the purpose 25 of supporting the front end of the load while at rest and during its motion rearwardly, and one or more rollers mounted upon a shaft resting in bearings extending rearwardly beyond the sills with means for rotating such 30 shaft and its rollers to move the load from off the wagon. To such a wagon I have added my improvements which consist first in providing adjustable means for tightening the endless chain employed in rotating the rollers

35 at the rear end of the wagon frame; second, in improved spring bearings for the front and rear axles and the manner of securing them to the wagon body; and third, in other details of construction which will be fully set forth.

40 I will now proceed to minutely describe the manner in which I have carried out my invention, and then claim what I believe to be novel.

45 In the drawings, Figure 1 is a side elevation of the wagon complete. Fig. 2 is an enlarged top plan view of the rear end of the wagon frame broken away to show the tightening device. Fig. 3 is an enlarged side elevation of the rear axle bearings. Fig. 4 is a 50 rear end view of the same. Fig. 5 is a perspective view of the two yoke blocks for the axle. Fig. 6 is a similar view of one of the

pedestals for the yoke blocks. Fig. 7 is a side elevation of the front of the wagon showing the front axle bearings, and Fig. 8 is a 55 detached detail view.

Referring to the drawings, 1. 1 are the sills of the frame, and 2. 2. are friction rollers (see Fig. 8), connected in a frame 3, the rollers resting upon the top face of and extending 60 transversely across the sills 1. 1. and adapted to reciprocate thereon for the purpose of supporting the front of the load while at rest and during its movement rearwardly.

4 is a shaft mounted in the rearwardly extending brackets 5. 5. on which are rigidly secured the rollers 6 upon which the rear end of the load rests. At the outer end of the shaft 4 is keyed the large sprocket-wheel 7 around which passes the chain 8, and 9 is a 70 small sprocket wheel around which the chain 8 also passes. The sprocket wheel 9 is mounted on the shaft 10 which also carries the double armed lever 11 for turning same, and 12 is a ratchet wheel, and 13' a dog for locking the shaft. On turning the handle 11 the chain 8 and two sprocket wheels 7 and 9 turn the rollers 6 to move the load rearwardly in dumping the same. The parts thus far described are shown and claimed in my patent 80 hereinbefore mentioned and form no specific part of my present invention.

As the chain 8 wears away from constant friction with the sprocket wheels it needs tightening and in order to provide for this I 85 secure upon the under side of the sill and floor of the wagon the plate 13 upon the under side of which the shaft 10 is journaled. In this plate 13 are three elongated slots 14. 14. and 15 running lengthwise of the wagon 90 and the plate is secured to the sill by bolts 16 passing through the slots 14. 14 and to the floor proper through the slot 15 by the bolt 17. The elongated slots permit of a forward adjustment of the plate and with it its journaled 95 shaft 10 and sprocket wheel 9 to the proper distance required to tighten up the chain 8 as it loosens through wear.

18 is the rear axle square in cross-section with the outer ends 19 for the reception of the 100 wheels. The metal pedestals which form the casing carrying the yoke-blocks and spring are similar in configuration and each consist of the lower flat body 20 having inwardly ex-

tending side flanges 21, 21, outer strengthening ribs 22 and outwardly projecting bottom lug 23. Its upper body 24 curves outwardly and inwardly on both sides having the upper 5 wall or bearing plate 25, and 26, 26, are openings for the passage of securing bolts 27 to lock the two sections together. On the inner edges of the upper walls 25 are the half-round notches 28 which when the pedestals are bolted 10 together form circular openings, and 29, 29 are upwardly projecting lugs upon the outer edges of the bearing-plates 25.

30 is the upper and 31 the lower yoke block between which the axle 18 is secured by the 15 bolts 32. The yoke block 30 has the half-square recess 33 upon its under side and the upwardly projecting extensions 34, 34. On either side and at each corner are the notches 35 extending from top to bottom.

20 A central top recess 36 receives the lower end of the spiral spring. The lower yoke-block 31 has the half square recess 36 upon its upper side which with the recess 33 in the yoke-block 30 forms when they are bolted together a square seat for the axle 18. Corner notches 37 in this block register with the notches 35 in the block 30. A brace 38 has secured to its rear end 39 by the rivet 40 the plate 41, having at each end the two upwardly 25 projecting lugs 42 and the end apertures 43.

The parts just described are assembled as follows: The pedestals 20, 24, are secured together by the bolts 27, 27 passing through the apertures 26, 26, to form a casing and these 30 are in turn secured in position by the central bolt 44 passing through the lower wall of the bracket 5, the cross-piece 45 and the central orifice 28 in the joined pedestals. End bolts 46, 46 pass up through the end orifices 28 in 35 the joined sections and through the cross-piece 45. The yoke-blocks 30 and 31 in which the axle 18 is securely bolted are then slid up between the lower ends 20 of the pedestals, the spiral spring 47 having been previously 40 placed in position its lower end resting in the socket 36 in the yoke-block 30. The side flanges 21 rest in the corner notches 35, 37, of the yoke-blocks. The plate 41 riveted at 40 to the brace 39 is brought under the lower 45 ends of the united pedestals and secured together through the apertures 23 in the pedestals and the apertures 43 in the plate 41 and brace 39 by the connecting bolts 48, the lugs 42 upon the plate 41 resting against the outer sides 20 of the united pedestals. In 50 this manner the yoke-blocks 30 and 31 carrying the axle have a vertical play within their casing against the action of the spiral spring 47, they being guided and controlled by the 55 flanges 21 playing in the notches 35, 37 of the yoke-blocks and the extensions 34, 34 upon the upper yoke block 30. The extensions 34, 34 present with the side walls of the yoke-blocks on extended bearing against the inner 60 faces of the pedestals 20 and reduces friction and consequently prevents undue wearing away of the surfaces in contact during verti-

cal play. The pedestals being secured at three points, viz., 43, 43, and 40 to the brace 38 through the plates 41 together with the 70 side-bearing of the lugs 42 upon the plate, it is practically impossible for a rupture or breakage to occur at this point of greatest strain.

The pedestals for the forward axle 18, (as 75 shown in Fig. 8,) are similar in construction and arrangement to the rear pedestals, the brace 57 to which its lower end is secured extending up to the sills on both sides as shown and there secured by bolts.

80 While I have shown my improved axle bearings as applied to my particular dumping wagon for lumber, it is apparent that they can be applied equally well to any other form of working wagon and I do not therefore wish 85 to confine their use to this particular application.

I claim—

1. In a lumber or other wagon, the box or casing for carrying the axle consisting of two 90 similar pedestals bolted together at the top and secured to the wagon frame, a brace to the lower end of which is bolted an intermediate plate, the lower ends of the united pedestals being bolted to either end of the intermediate plate and to the attached brace and upper and lower yoke blocks bolted around the axle and adapted for vertical play within the casing against the action of an inclosed spring substantially as shown and described. 95

100 2. In a lumber or other wagon, the box or casing for carrying the axle consisting of two similar pedestals provided with inner side flanges and bolted together at the top and secured by bolts and projecting lugs to the 105 wagon frame a brace to the lower end of which is bolted an intermediate plate, the lower ends of the united pedestals being bolted to either end of the intermediate plate and to the attached brace and upper and lower yoke blocks 110 bolted around the axle and provided with corner notches for engagement with the inner side flanges of the united sections and adapted for vertical play within the casing against the action of an inclosed spring substantially as shown and described. 115

120 3. In a lumber or other wagon the box or casing for carrying the axle consisting of two similar pedestals provided with inner side flanges and bolted together at the top and secured by bolts and projecting lugs to the wagon frame, a brace to the lower end of which is bolted an intermediate plate, the lower ends of the united pedestals being bolted to either end of the intermediate plate and to the attached brace and upper and lower yoke blocks 125 bolted around the axle and provided with corner notches for engagement with the inner side flanges of the united sections the upper block having upwardly projecting extensions 130 or guide-plates for the purpose stated, the blocks being adapted for vertical play within the casing against the action of an inclosed spring substantially as shown and described.

4. In a lumber or other wagon, the box or casing for carrying the axle consisting of two similar pedestals bolted together at the top and secured to the wagon frame a brace to the lower end of which is bolted the lower ends of the united pedestals and upper and lower yoke-blocks bolted around the axle and adapted for vertical play within the casing against the action of an inclosed spring substantially as shown and described.
5. In a lumber wagon the combination with the shaft carrying the lever and small sprocket wheel, the shaft carrying the large sprocket wheel and the rollers for removing the load and the chain connecting the two sprocket wheels, of the plate in which the first shaft is journaled provided with elongated slots substantially as and for the purpose stated.
6. In a lumber wagon the box or casing consisting of the two similar pedestals 20, 24 having the lower portion 20 provided with the side flanges 21, 21, and lower apertured lug 23 and the upper portion 24 having top bearing plate 25, provided with the half round notches 28 and lugs 29, the upper yoke-block 25 having corner notches 35 and half square recess 33, the upwardly projecting extensions 34 the lower yoke-block 31 with corner notches 37, the two adapted to be bolted together around the shaft, the spring 47 and the intermediate plate 41 apertured at 43, 43 and having lugs 42 at each end and riveted to the brace 39, the parts being joined together and to the wagon and operating substantially as shown and described. 35
- In testimony whereof I have signed my name to this specification in the presence of two subscribing witnesses.
